UNITED STATES PATENT OFFICE.

JOHN A. BARNARD, OF PHILADELPHIA, PENNSYLVANIA.

JET AGITATOR FOR FUEL-FEEDING DEVICES.

Application filed September 13, 1920. Serial No. 410,079.

To all whom it may concern:

Be it known that I, JOHN A. BARNARD, a citizen of the United States, residing at 2433 S. 21st St., Philadelphia, in the county 5 of Philadelphia and State of Pennsylvania, have invented certain new and useful Jet Agitators for Fuel-Feeding Devices, of which the following is a specification.

My invention relates particularly to securing continuity of coal delivery through a chute, illustrated in connection with underfed grates. It is applicable generally where soft coal is fed through a hopper and wedges or arches within the hopper or 15 adjacent thereto.

The purpose of my invention is to weaken the arch by a fluid jet or blast, preferably of air which may be directed from above or below as may be most convenient.

20 A further purpose is to provide a protected nozzle within the coal chute or hopper and in position to deliver the jet against an arch or jam of fuel, to break down the arch and renew the feeding of the fuel.

25 A further purpose is to provide intermittent operation of the blast preferably corresponding to movements of a fuel feeding mechanism to maintain uniform supply of the fuel.

30 A further purpose is to use a plurality of nozzles directed toward different positions where arches or jams are likely to occur so as to control the movement throughout a considerable range.

35 A further purpose is, where two or more jets are used, fed from a common source, to make that nozzle which is least protected from fuel ingress of smaller cross section than the section of one or other better protected nozzles, so that fuel accidentally entering through the first nozzle will be cleared through one of these other nozzles.

Further purposes will appear in the specification and in the claims.

45 My invention relates to the processes involved as well as to mechanism by which the processes may be carried out.

I have preferred to illustrate my invention by but one form thereof, selecting a 50 form which in use has proved to be simple, practical, efficient and inexpensive, and which at the same time well illustrates the principles of my invention.

Figure 1 is a vertical section through the 55 plunger casing showing a part of an under-

feed stoker to which my invention is applied, the driving mechanism being shown diagrammatically.

Figure 2 is a section upon line 2—2 of Figure 1.

Figure 3 is a fragmentary vertical section through the nozzles shown in Figure 1.

Figure 4 is a rear elevation of the structure seen in Figure 3.

Figure 5 is a longitudinal section of the 65 valve 37.

Because my invention finds the greatest utility known to me in the maintenance of a supply of fuel for the feeding mechanism of an underfed stoker and particularly because it has been tried out successfully by me in this connection, I have described the invention with reference to a common type of underfed stoker, intending to use this as typical of all automatic stokers as well 70 as use in various other arts where reliance is placed upon the substantial continuity of the fuel supply.

Applying to the stokers:—It is well known that banks of boilers having automatic supply of fuel for their grates do not yield the same return of water evaporated per pound of fuel in each boiler, owing, among other causes, to the arching of the fuel in the constricting walls of the 85 chute, pocket or boot within the bottom of which the feeding mechanism moves. The coal ordinarily used for this purpose is soft coal in which the larger lumps have been broken but which is otherwise “the run of 90 mine” and contains ungraded sizes from the maximum selected to culm.

When dry this fuel feeds by gravity with reasonable uniformity, notwithstanding the great variation in the sizes; but when it is damp it is disposed to arch where there is a constriction in the passage. As a result of this, the fuel supply of some stokers is seriously interrupted before the appearance of the fire or the poor vaporization from the boiler calls the attention of the boiler room force to the fact so that the trouble may be corrected.

In a large plant, a variation of so much as a tenth of a pound of coal per horse 105 power or kilowat developed is serious, so that the loss from this cause mounts up rapidly. My invention is intended to protect against stoppages of fuel flow by means of a fluid jet or blast, directed intermit- 110

tently (if for a plunger conveyor) against the point or points of usual stoppage and automatic in its action. I prefer to use air for my blast because it is the least expensive and does not add any injurious constituents to the coal. The moisture in steam is relatively low per volume of steam, but nevertheless the added moisture makes steam of less advantage in proportion to the 10 quantity of its moisture, which must be evaporated by the fire.

In Figure 1, I have shown an automatic under-feed stoker having front furnace wall 7, tuyère box 8, and fuel way 9, within which 15 the fuel is placed and advanced by a plurality of plungers of which two only are shown, at 10 and 11. The upper plunger is operated by the connecting rod 12 pivoted to it at 13 and the lower plunger is operated by rod 14 20 from a lower ram operating bar 15 connected to the connecting rod at 16 and to the bar 14 through pin 17 and a sliding collar 18.

Whatever the character of the hopper, chute or other fuel-feeding passage, my invention 25 contemplates the use of jets to break up arches of fuel which may be set up there and the number, placing and direction of the jets will depend upon the character, position and extent of the arches, whether determined by the design of the fuel passage or 30 by experience in operation.

Between the sleeve 18 and the collar 19 upon the bar 14, a number of U-shaped adjusting pieces 20 are placed, the number depending upon the extent of travel to the 35 right which is to be given to the ram 11. This ram is an agitator rather than a feeder for the fuel.

Movement of the operating lever 15 to the 40 left causes the sleeve 18 to engage a collar 21 upon the end of the rod 14, providing for the withdrawal of the plunger 11 to a fixed initial position in this type of stoker. The operating lever 15 is pivoted at a point below 45 the structure shown, and any other agitating plunger or plungers which are used may be similarly connected to it.

The connecting rod 12 is operated by a pin 22 in a crank 23 operating about a shaft 24 50 which, in this form, is driven by skew gear 25 meshing with a worm wheel 26, driven by a worm 27. In the illustration the worm is driven by a chain 28 and sprocket wheel 29. This construction is all old and forms one 55 means of many by which a plunger 10, operating in the ram box 30 or some other conveyor removes fuel from the bottom of a hopper here illustrated by the extension hopper 31.

60 The exact point or points at which arches are most apt to occur will differ with different shapes of the boot, with different pressures of coal and with various other differences which need not be considered and the 65 location of my blast in the present showing

has been selected with a view to taking care of the normal points of stoppage of fuel by arching which I have observed in installations of the type illustrated and which I have corrected by the mechanism shown. In the 70 particular construction of hopper shown experience has taught that arches of fuel commonly form in one or both of two locations, above or below the position of my nozzle holder 32 and I have therefore here illustrated two nozzles 33, 34, one directed upwardly to attack the under side of the upper arch and the other directed downwardly to attack the upper side of the lower arch. 75

The two nozzles take their fluid supply 80 from a common point 35, fed through pipe 36 and connections valved at 37 and connected to a compressed air pipe system 38 which is available as part of the stoker equipment. Couplings 39 are shown for convenience in attachment. Any fluid, liquid, gaseous or vapor, which can be driven as a jet will break up the arch, and the particular fluid must be chosen for its cheapness and ease of handling and to avoid injurious addition to the fuel. 85

In the illustration, Figure 2, the extension hopper 31 is provided with a number of boots 40, 40', 40², 40³ and parts 41 of the ram boxes for separate rams 10, each of 90 which parts and the stoker fed from it may be separately put out of service by a jam above the ram.

The jet supply is most desirably intermittent, because less fluid is required to 100 operate an intermittent jet, because the initial impacts of the jets yield a greater economy in the use of the fluid supply, and because operation of the jet while the plunger is out would serve no useful purpose and would tend to pack above the plunger. With a continuously operating conveyor the jet should be continuous. I recognize that the intermittent jet actuation could be so arranged in a variety of ways, (from different moving parts, for example) and show ram operation as the most convenient form only. I provide for engagement by the end 42 of the ram with a spring-retracted plunger 43 of the valve 37 with 115 each return of the ram, yielding a jet during the time that a ram is in its extreme position, and during this time only, while there is a place for the fuel to fall. The so-called "whistle valve," a well known article of manufacture, has proved an effective valve for this purpose and has been used by me successfully. 120

Though the nozzles 33 and 34, where two are used, can be formed separately, of any 125 material and shape desired, my wish to have the nozzles contracted at intermediate points such as 44 and of larger cross sectional area both to the front of that point as at 45 and at the outlets 46, 47, as well as 130

ease in mounting and cheapness of manufacture have led me to form the nozzles within cast blocks 48 secured to a suitable wall of the chute or hopper as by a bolt 5 49. In this casting I core the portions to the rear of the contractions 44 and drill and ream the flared portions 50 into them. I core the opening 51 which is threaded for attachment of the connecting pipe 36.

10 As will be recognized, the formation of the interior of the channels has to do with the efficiency in the jet in the delivery of as compact a stream as possible against the arch of fuel and does not directly affect 15 the broader aspects of my invention.

With the construction shown, it proves difficult to drill and ream exactly into the end of the cored portions 45 and for this reason, I have shown shoulders at 52 though 20 these shoulders have no special value in the construction shown.

I find it quite desirable that my nozzles shall project an appreciable distance into the column of fuel flowing and therefore 25 have them terminate at points 46 and 47, some distance from the sides of the casing, so as to strike the arches at effective points, a distance from the sides of the hopper to increase the benefit of the jets.

30 The opening 47 is protected from fuel inlet by its position below the protecting wall 53, but upwardly directed jets are in danger of being clogged by fuel crowding into them. In order to protect against this, 35 I provide a ledge 54 above the outlet 46. The wall 55 between this ledge and the outlet may to advantage be made substantially parallel to the line of travel of the jet. The upper edge 56 of the casting is made sharp 40 enough to avoid clogging of fuel against it.

I prefer to make the cross sectional area of the upper nozzle, and particularly of its 45 point of smallest cross section, smaller than that of smallest cross section of the lower nozzle, in order that any fuel which may be forced in through the upper nozzle will drop into the lower nozzle between the times of operating the jets and be driven out freely through the lower nozzle.

50 In operation, every return movement of the ram 10 presses the valve stem and causes fluid jets to engage any arches which may be present breaking them down and renewing fuel flow. This occurs at the time when 55 the conveyor (ram) is in position to receive and handle more fuel.

I recognize that any number of nozzles 60 may be used within a single hopper and that characters of nozzle may be greatly varied to carry out my invention; also that with knowledge of my invention different 65 designers will prefer to construct the device in various ways as their preference or special needs may direct. I purpose including herein all of these various forms which come

within the reasonable spirit and scope of the claims.

Having thus described my invention, what I claim as new and desire to secure by Letters Patent is:—

70 1. In a feeding device for fuel, walls forming a passage down which the fuel passes by gravity, a nozzle adapted to discharge a fluid jet within the passage in position to break down any arches of fuel 75 formed, a cover for the nozzle orifice protecting it from flow of fuel, connections for furnishing fluid supply under pressure to said nozzle, a valve and mechanically actuated means for intermittently operating it 80 to control the supply.

2. In a fuel feeding device, walls forming a restricted passage within which the fuel is likely to arch, a nozzle extending out into the passage and discharging upwardly in a 85 direction diagonal to the passage, a supplemental cover protecting the outlet of the nozzle from flow of fuel, and connections for furnishing air supply under pressure to said nozzle.

90 3. In a fuel feeding device, walls forming a restricted passage within which the fuel is likely to arch, nozzles directed at different angles with respect to the fuel flow, one diagonally upward to attack different arches 95 of fuel, and overhang means for protecting the openings of the nozzles from stoppage by fuel flow, in combination with connections providing pressure fluid supply for said nozzles.

100 4. In a fuel feeding device, walls forming a restricted passage within which the fuel is likely to arch, in combination with a plurality of nozzles adapted to discharge 105 into the passage directed one generally upwardly and the other at an angle thereto and connecting with a common inlet passage, the upwardly directed nozzle being of smaller cross section than the one at an angle thereto and the outlets of both nozzles 110 out of direct line of fluid flow, and connections for supplying fluid under pressure to said nozzles.

115 5. In a fuel feeding device, walls forming a restricted passage within which the fuel is likely to arch, a nozzle discharging into said passage diagonally upward and of smaller cross section at an intermediate point near the orifice than at the orifice or 120 back of that point, means for protecting the nozzle outlet from the direct line of fuel flow and connections for providing fluid pressure supply to said nozzle.

125 6. A nozzle for use in breaking down arches of fuel in lines of fuel flow, said nozzle having a passage way of decreasing cross section from the point of supply toward the outlet, a constriction near the outlet and an upwardly flared passage from the point of constriction to the outlet, in com- 130

bination with an overhang above the outlet protecting it from fuel flow, and walls forming a fuel feeding passage within which the nozzle projects to discharge against fuel arches therein.

7. In a nozzle for use in breaking down arches of fuel in lines of fuel flow, a cast body providing a cored passage extending from the point of supply connection toward 10 the outlet and outwardly flaring cut passages from the termination of the cored passage to the point of discharge, one of the passages extending upwardly and another downwardly, in combination with 15 walls forming a gravity fuel passage within which the upwardly and downwardly directed passages are located.

8. In a device for use in breaking down arches of fuel in lines of fuel flow, walls 20 forming a common inlet and nozzles therefrom, one of which points upwardly and another downwardly the upwardly directed nozzle having its smallest cross section of less area than the smallest cross section of 25 the other.

9. In a device for use in breaking down arches of fuel in lines of fuel flow, walls forming a common inlet, nozzles therefrom, one of which points upwardly and the other 30 downwardly, the upper nozzle having its smallest cross section of less area than the smallest cross section of the other, in combination with a protecting cover above the first nozzle and walls forming a gravity 35 fuel feeding passage within which the nozzles project.

10. In a nozzle for use in breaking down arches of fuel in lines of fuel flow, a block 40 having two connecting cored passages therein, one upwardly and the other downwardly directed and having upwardly and downwardly cut outwardly flaring passages leading therefrom, respectively, the smallest cross section of the upwardly directed passage being of less area than that of the downwardly directed passage, in combination with walls forming a gravity fuel feeding passage within which the block is located.

50 11. In a nozzle for use in breaking down arches of fuel in lines of fuel flow, an upwardly directed nozzle located in the line of flow of the fuel and a protecting cover for the said nozzle extending diagonally upwardly and outwardly further into the line of flow from the orifice of said nozzle, in combination with walls forming a gravity fuel passage for the fuel flow.

60 12. In a fuel feeding device for stokers, walls forming a passage way for gravity feeding of the fuel, an intermittently actuated conveyor feeding the fuel at intervals from the bottom of the passage, a nozzle directed into the passage toward the posi-

tion of probable fuel arches therein, a supply of fluid pressure for said nozzle, a controlling valve for said supply and actuating connections for said valve, timed to cause flow of fluid at intervals corresponding to conveyor actuations, and between successive 70 actuations.

13. In a fuel feeding device for stokers, walls forming a passage down which the fuel is fed by gravity, an intermittently actuated conveyor removing the fuel from the 75 bottom of the passage at intervals, a nozzle directed within the passage and adapted to play upon an arch of fuel therein, a source of fluid pressure supply for said nozzle, a valve controlling the supply to the nozzle 80 and an automatic means for actuating the valve operated by one of the movable conveyor parts and timed to actuate the valve at intervals between successive fuel removing 85 operations of the conveyor.

14. In a fuel feeding device for stokers, walls forming a passage down which the fuel is fed by gravity, an intermittently actuated conveyor removing the fuel from the bottom of the passage at intervals, a 90 nozzle directed within the passage and adapted to play upon an arch of fuel therein, a source of fluid pressure supply for said nozzle, a valve controlling the supply to the nozzle, and an operating connection 95 between the valve and conveyor opened by the conveyor during retracting movement.

15. In a fuel feeding device for stokers, walls forming a passage down which the fuel is fed by gravity, a plunger conveyor removing the fuel from the bottom of the passage at intervals, a nozzle directed within the passage and adapted to play upon an arch of fuel therein, a source of fluid pressure supply for said nozzle, and an automatically closed valve controlling the supply to the nozzle, having opening connections engaged by the conveyor parts when the conveyor plunger is in retracted position.

16. The method of breaking up arches of fuel in a gravity feeding system for a plunger conveyor which consists in directing a fluid jet upon the arch at intervals and timing the intervals to correspond with retracted positions of the plunger.

17. The method of breaking up arches of fuel in a gravity feeding system for a plunger conveyor which consists in directing a fluid jet upon the arch from within the path of fuel flow, starting and stopping the jet by valve control of the fluid supply and in synchronizing the valve operation to the movement of the conveyor mechanism, so that flow of the jet corresponds with retracted positions of the plunger.
